UNITED STATES PATENT OFFICE.

DOSITHE BERNARDIN, OF ST. EUSTACHE, AND ZENOPHILE PATTENAUME, OF WINNIPEG, CANADA, ASSIGNEES OF FORTY-NINE ONE-HUNDREDTHS TO JAMES G. BENNETT AND HERBERT G. WILSON, OF WINNIPEG, CANADA.

AUTOMATIC RAILWAY-GATE.

SPECIFICATION forming part of Letters Patent No. 615,787, dated December 13, 1898.

Application filed June 4, 1898. Serial No. 682,555. (No model.)

To all whom it may concern:

Be it known that we, DOSITHE BERNARDIN, of St. Eustache, and ZENOPHILE PATTENAUME, of Winnipeg, in the Province of Manitoba and Dominion of Canada, have invented a new and Improved Automatic Railway-Gate, of which the following is a full, clear, and exact description.

Our invention relates to that class of rail-way-gates designed to be operated automatically to bar a highway before the train reaches the crossing and to free the highway after the train passes across it.

Our invention comprises the novel features of construction and combinations of parts which will be hereinafter described, and defined in the claims.

Reference is to be had to the accompanying drawings, forming a part of this specification, in which similar characters of reference indicate corresponding parts in all the figures.

Figure 1 is a top plan view of the gate. Fig. 2 is a side elevation thereof. Fig. 3 is a side elevation, on a larger scale, of the two operating-levers which are directly connected to the gate mechanism. Fig. 4 is a sectional plan view taken upon the line 4 4 of Fig. 3. Fig. 5 is a detail plan view of the lever connecting the longitudinal and transverse shafts. Fig. 6 is a side elevation of the same. Fig. 7 is a section taken upon the line 7 7 of Fig. 6. Fig. 8 is a side elevation of the same parts shown in Fig. 6 as applied to the other set of operating-levers. Figs. 9 and 10 are elevations of the suspended bars for closing the roadway. Fig. 11 is an elevation of one of the forked levers by which the gate mechanism is operated. Figs. 12 and 13 are respectively a side elevation and a plan view of the lever secured to the longitudinal shaft and engaging the bar which is directly moved by the car-wheels, and Fig. 14 is a cross-section through the supports for the suspended bars shown in Figs. 9 and 10.

The object of our invention is to provide an apparatus which is automatically operated by a railway-train or its motor to close a highway-crossing of a railway previous to the approach of the train or motor and to open

the crossing after the train or motor has passed, which mechanism is of such a nature that it requires no attention from the engineer or motorman, being entirely automatic in its action.

This mechanism consists of two principal parts—the operating mechanism, which is of that class having a bar in position to be engaged by the tread of the wheels, and the gate or closing mechanism, which is operated by said bar through suitable connecting mechanism.

The highway is closed in the following manner:

Upon opposite sides of the highway are erected posts A', which are connected at their upper ends by a beam A, said posts being at such a distance apart and of such a height as to furnish ample opening for any vehicles which are liable to use the highway. Upon the beam A are pivoted two bars B by pivots B', which are at or near their centers. These beams are constructed as shown in cross-section in Fig. 14, and each consists of a central body B², upon opposite sides of which are placed the plates B³, which extend below the bar B², forming the central body, and at their lower edges are provided with inwardly-turned flanges B⁴, which do not quite meet in the center, thus leaving a slot B⁵ extending the length of the bar. At their center or where the pivot is to be located the plates B³ have ears extending above the bar B² and provided with apertures B⁷ to receive the pivots B'. At one end—that is, the end which is at the side of the roadway—the plates B³ are connected by a cross-pin B⁶, to which is attached a chain b⁶, which limits the motion of the rods b, supported from the bars B, which rods are of such a length as to reach to near the ground. At their upper ends the rods b are each attached to a ring b², said ring being attached to a T-shaped slide b', provided at its upper end with a cross member b³. The shape of this slide is clearly shown in Figs. 9 and 10. The cross bar or head b³ fits within the slot formed between the lower edges of the plates B³ and is free to slide therein. The successive slides b' are

secured to each other by means of rings or links b^4 , which enter apertures b^5 in the slides b' . These links limit the separation of the rods b . When the bars B are tilted at an angle, as shown in Fig. 2, the slides b' will move toward the lower end of the bar. When the bars are in the position shown by the full lines in Fig. 2, the slides b' and the rods b , suspended therefrom, will move toward the center of the roadway, so as to block the same. When the bars B are tilted in the opposite direction, as shown by the dotted lines in Fig. 2, the rods b will be slid toward the outer side of the roadway, as shown by the dotted lines at one side of the figure. This opens the roadway and leaves it unobstructed.

To the inner ends of the tilting bars B are attached links C^3 , which at their upper ends are attached to an arm C^2 , secured to a shaft C , mounted in bearings on the brackets C^4 , which are supported from the beam A . The shaft C at one end is provided with a flattened portion C' , which is also twisted, so as to give it a quarter-turn.

Upon the frame which supports the beam A is pivoted a lever D , which at its upper end is divided into two parallel forks D' , which embrace the flattened portion C' of the shaft C . If the lever D be swung upon its pivot, the two forks will embrace the sides of the twisted portion of the shaft C , so as to rotate it, giving it a quarter-turn. This will raise or lower the inner ends of the tilting bars B , depending upon the direction of motion of the lever D . To the lower end of the lever D is attached a chain D^2 , which passes around the pulley D^3 , mounted upon one of the posts A' . This chain extends to one side or in a direction parallel with the track, as two separate runs, passing through guides D^6 , mounted upon one of the posts A' and a post D^4 , which is located near the operating mechanism. Both ends of the chain pass over guide-pulleys D^7 , mounted upon a frame I , one end being attached to the pivoted operating-lever E and the other, after passing about its guide-roller, being attached to the upper end of the other pivoted operating-lever E' . The ends of the chain are not attached rigidly to the levers, but are attached to rods d' , which pass through apertures in the levers E and E' and have springs d between their outer ends and the levers, thus forming yielding attachments of the chains to the levers.

Mounted in suitable bearings K^2 outside of and parallel with the rails R are shafts K . Four of these shafts are shown, two shafts being used in one set of operating mechanisms and the other two in the other set. These operating mechanisms are furnished in duplicate, the construction of the greater part thereof being exactly alike. The corresponding parts of the two sets are therefore similarly lettered, and the description of one set applies to the other, except where hereinafter otherwise definitely stated.

The two shafts K of each set are located

one upon each side of the track, being only a short distance outside of the rail. Upon the bearing-blocks K^2 , which support the shafts, are pivoted levers L' , which at their free ends are connected to a bar L , located close along the outer side of the rail. This bar is preferably of a **U** cross-section, the open side facing outward or away from the rail. Between the two side portions of this bar enter the outer ends of arms K' , secured upon the shafts K . These arms are shown in detail in Figs. 12 and 13. The outer ends k of these arms are not secured directly to the bars L , but are slightly rounded or pear-shaped, as shown in Fig. 12, and lie between the top and bottom portions of the bars L . The ends of the bars L are bent downward a little, as shown in Fig. 2. When the bars L are depressed by engagement with the car-wheels, the shafts K will be rocked in their bearings. To the shafts K' are secured arms M , which at the ends adjacent the rail carry set-screws m , which bear upon the upper surface of arms N , pivoted to plates N' , secured upon the upper surfaces of the ties. The swinging ends of the arms N are connected to links P , which at their lower ends are pivoted to arms O , secured by means of set-screws O' upon a transverse shaft F , extending across the track and beneath the rails. Depression of the bars L will therefore result in a rocking movement being given to the lateral shaft F . The mechanism heretofore described for securing the movement is duplicated upon each side of the track. This duplication is not, however, strictly necessary, as it may be found that one set of such devices located upon one side of the track only is sufficient to secure the desired results. We do not therefore desire to be limited to the use of both sets of these devices.

At any suitable point upon the shaft F is fixed an arm Q , which is engaged by a spring Q' , so as to rock the shaft F in opposition to the movement caused by the depression of the bars L . This spring may, however, be inserted at any other point in the mechanism found more desirable and may be of any suitable construction.

At one end of the shaft F —that is, the end upon the same side of the track as that occupied by the highway-gate—are journaled the operating-levers E and E' . The two sets of operating mechanism are exactly alike in the parts heretofore described. The operating-levers E and E' are, however, slightly different, and the mechanism for controlling and operating the same differs in appearance, although the principle is substantially the same in both cases. The operating-lever E is the one which acts upon the gate mechanism to close the highway, while the operating-lever E' is the one which operates upon the same mechanism to open the highway.

Upon the ends of the shafts F and F' belonging to the two sets of mechanism are secured arms G and G' , both having the same

function, but being slightly different in construction. These arms are adapted to be locked to the operating-levers E and E' when the mechanisms controlled thereby are to be operated. The operating-levers E and E' have side extending arms E² E³, to the outer ends of which are pivoted the locking-bars H and H'. The locking-bar H extends in a horizontal direction, while the locking-bar H' extends in a vertical direction. Each of these locking-bars is provided with a notch H², adapted to engage the ends of the fixed levers G and G', so as to lock the operating-levers E and E' to their respective shafts. The notch H² in the locking-bar H is in one side thereof and intermediate its length, while the corresponding notch in the locking-bar H' is at the end thereof. The locking-bar H' is connected to the operating-lever E by means of a link J, pivoted at J³ and J⁴ to the bar and lever. The link J is also pivoted intermediate its ends to the locking-bar H by means of the link J', which is provided with a slot J² at the point where it is connected to the link J. This allows for a certain amount of play of the locking-bar H in one direction. As shown by the solid lines in Fig. 3, both of the locking-bars H H' are in engagement with their respective arms G and G', so that both operating-levers E and E' are secured to the shafts F and F'. If, however, the operating-lever E is thrown into the position shown by the dotted lines in Fig. 3, it will release the locking-bar H' by said movement, so as to free the operating-lever E' from its shaft. The operating-lever E' will thus be kept disengaged from its shaft as long as the lever E is thrown backward. If, however, the lever E' is operated so as to be thrown into its outer position, as shown by the dotted lines in Fig. 3, the locking-bar H will be lifted, so as to free the operating-lever E from its shaft, said lever being held disengaged as long as the operating-lever E' is held backward. As a consequence, whichever set of operating mechanism is first engaged by the car-wheels will disengage the operating-lever of the other set, so that the other set of operating mechanism will have no effect upon the gate. The train approaching the gate will thus engage the first set of operating mechanism, so as to close the highway-crossing, and will keep the same closed until after the car-wheels have left the first set of operating mechanism. As soon as the car has left this first set of operating mechanism the locking-bar of the second set will be allowed to drop into position, so that the car-wheels before they leave the second set of operating mechanism will be enabled to operate through said mechanism to open the gate, and thus free the highway-crossing. It will thus be seen that this mechanism is in every sense automatic, as it requires no attention whatever from the engineer or motor-man.

The operating-levers E and E', as herein shown, are constructed of plates bent into shape. They are limited in motion by rods I, which connect the plates forming the frame I. The range of motion of the levers E and E' may be regulated by means of the set-screws m in the arm M. By forcing this set-screw farther down the position of the bars L, which engage the car-wheels, is regulated and the scope of their motion is increased.

Having thus fully described our invention, we claim as new and desire to secure by Letters Patent—

1. A railway-gate, comprising a beam or support extending across the highway, bars pivoted thereon and extending in the same direction, a series of rods suspended from and adapted to slide on said bars, a flexible connection between said rods and connected to one end of the bars to limit their separation, an arm pivoted on the beam, links connecting the arm with both pivoted bars, a movable bar adapted to be engaged by the car-wheels, and connections therefrom to the arm which controls the pivoted bars, substantially as described.

2. A railway-gate, comprising a beam or support extending across the highway, two bars pivoted thereon and extending in the same direction, a series of rods suspended from and adapted to slide on said bars, a flexible connection between said rods, limiting their separation, and connected to one end of the bars, a shaft journaled on the beam and having a flattened and twisted section, an arm on said shaft, links connecting the arm with the pivoted bars, a pivoted lever embracing the twisted section of the shaft, and a train-operated mechanism for swinging the pivoted lever, substantially as described.

3. A railway-gate, comprising a beam or support extending across the highway, two bars pivoted thereon and extending in the same direction, a series of rods suspended from and adapted to slide on said bars, a flexible connection between said rods, limiting their separation, and connected to one end of the bars, a shaft on the beam and having a flattened and twisted section, an arm on said shaft, links connecting the arm with the pivoted bars, a pivoted lever embracing the twisted section of the shaft, a movable bar adapted to be engaged by the car-wheels, and operative connection therefrom to the pivoted lever, substantially as described.

4. A railway-gate, comprising a beam or support extending across the highway, two bars pivoted thereon and extending in the same direction, a series of rods suspended from and adapted to slide on said bars, a flexible connection between said rods, limiting their separation, and connected to one end of the bars, a shaft journaled on the beam and having a flattened and twisted section, an arm pivoted on said shaft, links connecting the arm with the pivoted bars, a pivoted lever embracing the twisted section of the shaft, two bars extending alongside the rail and adapted to be depressed by the car-wheels,

connections from each of said bars to the pivoted lever, to throw it in opposite directions, and means operated by the bar first engaged by the car-wheels, to disconnect the other until it is itself freed from engagement with the wheels, substantially as described.

5. A railway-gate, comprising a pivoted bar extending across and above the highway, and having a T-slot or downwardly-opening tubular passage formed in its lower side, a series of slides having heads loosely fitting said passage and freely sliding therein, a flexible connection between the slides, which limits their separation, and is connected at one end with the bar, rods suspended from the slides, two bars extending alongside the rail and adapted to be depressed by the car-wheels, connections from each of said bars to the pivoted lever, to throw it in opposite directions, and means operated by the bar first engaged by the car-wheels, to disconnect the other until it is itself freed from engagement with the wheels, substantially as described.

6. A railway-gate-operating device, comprising duplicate operating mechanisms, each consisting of a shaft journaled alongside the rail, having a bar supported therefrom and adapted to be engaged by the car-wheels, a shaft extending transverse the track, arms upon said shafts, connections therebetween, and a gate-operating arm upon the transverse shaft of each set, and means operated by the bar first engaged by the car-wheels, to disengage the gate-operating arm of the other set 35 of operating mechanisms, substantially as described.

7. A railway-gate-operating device, comprising duplicate operating mechanisms, each consisting of a shaft journaled alongside the

40 rail, having a bar supported therefrom, and adapted to be engaged by the car-wheels, a shaft extending transversely of the track, arms upon said shafts, connections between said arms, a gate-operating arm loosely mounted on the lateral shaft, an arm fixed on said 45 shaft, and a dog or locking-arm pivoted upon the loose operating-arm and adapted to engage the fixed arm, and connections from each loose operating-arm to the dog or locking-arm of the other set, whereby the set of operating 50 mechanism which is first engaged by the car-wheels releases the operating-arm of the other set, substantially as described.

8. A railway-gate-operating device, comprising duplicate operating mechanisms, each 55 consisting of a shaft journaled alongside the rail, and having a bar supported therefrom and adapted to be engaged by the car-wheels, a shaft extending transversely of the track, arms upon said shafts, connections between 60 said arms, a gate-operating arm loosely mounted on the transverse shaft, an arm fixed on said shaft, and a dog or locking-arm extending laterally of the fixed arm, said locking-arm having a side notch adapted to engage 65 the end of the fixed arm to lock the two arms together, and a link pivoted on each gate-operating arm and connected with the locking-arm of the opposite set of mechanisms, whereby the set of operating mechanisms 70 which is first engaged by the car-wheels releases the gate-operating arm of the other set, substantially as described.
